UNITED STATES PATENT OFFICE.

RODERICK R. MACKENZIE, OF WALLACE, IDAHO.

PEN.

1,209,602.

Specification of Letters Patent. Patented Dec. 19, 1916.

Application filed June 3, 1916. Serial No. 101,535.

To all whom it may concern:

Be it known that I, RODERICK R. MACKENZIE, a citizen of the United States, residing at Wallace, in the county of Shoshone, State of Idaho, have invented a new and useful Pen; and I do hereby declare the following to be a full, clear, and exact description of the invention, such as will enable others skilled in the art to which it appertains to make and use the same.

The present invention relates to certain new and useful improvements in pen holders, and more particularly to that type of pen holders which are adapted to be held between the first and second fingers of the hand when in use, the object of the invention being to provide a pen holder which embodies novel features of construction whereby the amount of hand and finger energy necessary to grip the pen is greatly reduced, thereby overcoming or reducing to a minimum the hardships of writing such as cramps, fatigue, nervousness and the like, at the same time securing to the writer a much better control over the movements of the pen than is possible with the ordinary pen holder.

Further objects of the invention are to provide a pen holder of this character which holds the pen point in such a manner that it bears evenly upon the surface of the paper and will not scratch or puncture the paper, which can be used to advantage by the large number of people whose occupations cause such physical strain and fatigue as to render their hands, for the purpose of writing, nervous, shaky and unsteady, thus making steady uniform writing almost impossible and resulting in a dislike for writing, which can also be advantageously used by those who are subject to "writers' cramps" or other disagreeable sensations of the hands or fingers caused by the strain resulting from the use of the ordinary pen, and which will evenly distribute the pressure between the two halves of the pen point, thereby preventing the pen point from being prematurely rendered unfit for use.

In devising a pen of this character it was found that the only way in which these results could be obtained was by adjusting the pen in such a manner that the writing point would be at an angle to the stem. This angle can be obtained in numerous different ways, and the barrel can be mounted in such a

manner as to be susceptible of adjustment to either a right-hand or left-hand inclination.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a top plan view of a pen holder constructed in accordance with the invention, showing the barrel and finger piece properly adjusted for the reception of a fine pointed pen. Fig. 2 is a side elevation of the same, the manner in which the pen point can be rotated within the barrel being indicated by dotted lines. Fig. 3 is a top plan view of the pen holder, showing the same as properly adjusted for use in connection with a stub pen. Fig. 4 is a detached perspective view of the pen point receiving barrel. Fig. 5 is an enlarged transverse sectional view through the pen, on the line 5-5 of Fig. 2. Fig. 6 is an enlarged longitudinal sectional view through the pen point receiving barrel or sleeve. Fig. 7 is an enlarged detached perspective view of the finger engaging clin, and Fig. 8 is a detail view showing a slightly modified construction of finger engaging clip.

Corresponding and like parts are referred to in the following description and indicated in all the views of the drawing by the same reference characters.

Specifically describing the present embodiment of the invention, the numeral 1 designates the stem of the pen holder, said stem being designed to be received between the first and second fingers of the hand, and preferably tapering in cross section toward the upper end thereof. The base or lower end of the stem 1 is formed with a central opening or bore 2, and a longitudinally extending radially disposed slot 3 leading from one side of the stem to the bore. If desired, the slotted and apertured base of the stem may be reinforced in any suitable manner.

The barrel 4 has a tubular formation, and is mounted upon the base of the stem 1 in such a manner as to project beyond the same and be disposed at an acute angle to the axis

thereof. A wing 5 projects from one side of the barrel 4, said wing being arranged in a plane through the axis of the barrel, and being inclined rearwardly at an acute angle 5 to the barrel. This wing 5 is designed to be received within the radial slot 3 of the stem 1, and is provided at the forward edge thereof with an enlarged rib 6 which fits within the bore 2 of the stem 1. The wing 5 can thus be slipped longitudinally into position within the slot 3 from the base or lower end of the stem 1, although it is held securely against lateral movement therein, by reason of the interlocking connection between the 15 rib 6 and the bore 2.

A sleeve 7 is rotatably mounted within the barrel 4, being suitably split at one end thereof, as indicated at 8, so as to coöperate with the inner walls of the barrel to grip a 20 pen point 9 in the usual manner. The opposite end of the sleeve 7 may terminate in a flange 10 which extends around the end of the barrel so as to be grasped by the fingers when it is desired to rotate the sleeve within 25 the barrel. In the present instance the barrel is shown as surrounded by an exterior covering 4^a, and the barrel and sleeve 7 have corresponding annular crimps 11 which prevent longitudinal sliding movement of the 30 sleeve within the barrel. When a fine pointed pen 9 is used, the barrel 4 is inclined in one direction with respect to the stem 1, as indicated by Fig. 1, while when a stub pen 9^a is used, the barrel 4 is inclined in the opposite direction with respect to the stem 1, as indicated by Fig. 3. In either case the pen point must project from the top of the barrel 4, and it will be obvious that with the 35 present construction the pen point can be 40 inserted in the barrel on any side thereof, or rotated therein after being inserted.

The finger engaging clip is susceptible of many modifications, the essential feature being to provide annular faces which can be 45 adjusted upon the stem and brought into proper position for engagement with the two fingers of the hand to hold the stem against rotation, without the necessity of a strong pressure being exerted thereon by the fingers. 50 This finger engaging clip may include an outer arm 12 adapted to engage the exterior of the stem 1, and an inner arm 13 adapted to be inserted within the slot 3 of the stem and wedged in position between one 55 of the side walls of the slot and the wing 5. The outer arm 12 is formed with the two finger receiving seats 12^a and 12^b which are arranged at an angle to each other so as to be readily engaged by the two fingers of the 60 hand; and the clip itself may be formed of spring material so as to grip the stem and have a tendency to retain itself in position 65 thereon. The entire clip is reversible, so that the finger engaging seats 12^a and 12^b thereof can always be brought to the top of the stem,

according to the adjustment of the barrel 4. These two different positions of the barrel and finger engaging clip are indicated quite clearly by Figs. 1 and 2. The finger engaging clip can also be longitudinally adjusted 70 upon the stem and locked in the position which may be most convenient to the writer. After the parts have been adjusted, the arm 13 of the clip and the wing 5 of the barrel are wedged within the slot 3 of the stem in 75 such a manner as to lock the parts in position.

A slightly modified construction of finger engaging clip is indicated by Fig. 8. A ring 14 is here shown as slidably mounted upon 80 the stem 1, said ring being provided upon one side thereof with the angularly disposed finger engaging seats 14^a and 14^b, and being also provided with an inwardly projecting arm 15 adapted to be received within the slot 85 3 of the stem. This form of finger engaging clip can be adjusted longitudinally upon the stem, and reversed thereon, in exactly the same manner as the first form of finger engaging clip. The finger receiving seats of 90 the clip are easily engaged by the fingers of the hand so that a very slight pressure is sufficient to hold the stem against rotation within the hand. A firm and easy control of the pen is secured, since the fingers have 95 a double hold on the pen, and it is not necessary to apply but a fraction of the finger pressure required by the usual pen and which is so fatiguing to the majority of penmen, often resulting in writers' cramps and 100 an inability to continue writing. Where the pen is held between the first two fingers of the hand, the energy expended through and by the fingers is reduced to a minimum and at the same time the writer or penman retains perfect control over the pen, being enabled to use the same for long periods of 105 time without fatigue.

Having thus described the invention, what I claim as new and desire to secure by Letters Patent, is:—

1. A pen holder including a stem having a longitudinally extending and radially disposed slot in the base thereof, a barrel, a wing projecting laterally from one side of the barrel and arranged at an acute angle to the axis thereof, said wing being adapted to be received within the slot of the stem, and a substantially U-shaped clip, one of the arms of the clip being adapted to enter 115 the slot of the stem, while the other arm provides a finger receiving seat on the exterior of the stem.

2. A pen holder including a stem having a longitudinally extending and radially disposed slot in the base thereof, a barrel, a wing projecting from one side of the barrel and extending at an acute angle thereto, said wing being adapted to be inserted in the slot 125 of the stem, and a finger engaging clip 130

mounted upon the stem and formed with an arm projecting into the slot thereof, said clip being also formed with a pair of angularly disposed finger receiving seats.

5 3. A pen holder including a stem having a longitudinally extending and radially disposed slot in the base thereof, a barrel, a wing projecting laterally from one side of the barrel and arranged at an acute angle 10 to the axis thereof, said wing being adapted to be received within the slot of the stem, and a substantially U-shaped spring clip formed with an arm adapted to enter the slot of the stem and an arm adapted to engage the exterior of the stem, the latter mentioned arm being formed with a pair of angularly disposed finger receiving seats.

4. A pen holder including a stem provided 20 at the base thereof with an axial bore and a

radially disposed slot, a barrel, a wing projecting laterally from one side of the barrel and disposed at an acute angle to the axis thereof, said wing being adapted to enter the slot of the stem and being provided with 25 a rib adapted to enter the bore of the stem, and a reversible finger piece adjustably mounted upon the stem, said finger piece including an arm which enters the slot of the stem, and being formed with angularly disposed finger receiving seats adapted to be positioned upon either side of the stem. 30

In testimony whereof I have signed my name to this specification in the presence of two subscribing witnesses.
